United States Patent Office

Des. 224,903
Patented Oct. 10, 1972

224,903

HACKSAW FRAME

Raymond C. Dreier, 3450 N. Lake Shore Drive,
Chicago, Ill. 60657

Filed Jan. 11, 1971, Ser. No. 105,781

Term of patent 14 years

Int. Cl. D8—03

U.S. Cl. D8—96

FIG. 1

FIG. 2

FIG. 4

FIG. 3

FIG. 1 is a side elevational view of a hacksaw frame incorporating my new design;

FIG. 2 is a top plan view of FIG. 1;

FIG. 3 is a front elevational view taken from the left of FIG. 1; and

FIG. 4 is a rear elevational view taken from the right of FIG. 1.

I claim:

The ornamental design for a hacksaw frame, substantially as shown and described.
